United States Patent Office

Des. 188,741
Patented Aug. 30, 1960

188,741

FONT OF TYPE

Richard K. Gerlach, Gardena, Calif., and Paul M. Koons,
Dayton, Ohio, assignors to The National Cash Register
Company, Dayton, Ohio, a corporation of Maryland

Filed Oct. 30, 1959, Ser. No. 58,127

Term of patent 14 years

(Cl. D64—12)

The figure on the drawing is a face view of a font of type showing our new design.

We claim:

The ornamental design for a font of type, substantially as shown.
